US0D1078615S

(12) **United States Design Patent** (10) **Patent No.:** **US D1,078,615 S**
(45) **Date of Patent:** **** Jun. 10, 2025**

(54) **BATTERY CASE**

(71) Applicant: **Qiufei Yang**, Guangdong (CN)

(72) Inventor: **Qiufei Yang**, Guangdong (CN)

(**) Term: **15 Years**

(21) Appl. No.: **29/996,047**

(22) Filed: **Mar. 30, 2025**

(51) LOC (15) Cl. **13-02**

(52) U.S. Cl.

USPC **D13/103**

CLAIM

The ornamental design for a battery case as shown and described.

DESCRIPTION

FIG. 1 is a perspective view of the battery case showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines depict portions of the battery case and form no part of the claimed design.

1 Claim, 8 Drawing Sheets
